(57) **CLAIM**

The ornamental design for a chainsaw scabbard, as shown and described.

DESCRIPTION

FIG. 1 is a front, right side perspective view of a chainsaw scabbard showing my new design;

FIG. 2 is a rear, left side perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is a front, right side perspective environmental view; and,

FIG. 10 is a rear, left side perspective environmental view thereof.

The portions shown in broken lines are included for illustrative purposes only and form no part of the claimed design. The drawings include surface shading that represents contour and not surface ornamentation.

1 Claim, 8 Drawing Sheets
